UNITED STATES PATENT OFFICE.

BRADFORD F. LANCASTER, OF AUGUSTA, MAINE, ASSIGNOR OF ONE-HALF
TO RICHARD W. BLACK, OF SAME PLACE.

RATCHET-WRENCH.

SPECIFICATION forming part of Letters Patent No. 282,462, dated July 31, 1883.

Application filed May 31, 1883. (No model.)

To all whom it may concern:

Be it known that I, BRADFORD F. LANCASTER, a citizen of the United States, residing at Augusta, in the county of Kennebec and State of Maine, have invented certain new and useful Improvements in Ratchet-Wrenches, of which the following is a specification, reference being had therein to the accompanying drawings.

10 My invention relates to ratchet-wrenches; and the object of my invention is to produce a ratchet-wrench which shall be capable of working nuts of any size with a ratchet motion, and which may also be used without a 15 ratchet motion as an ordinary monkey-wrench. I accomplish this result by means of the mechanism shown in the accompanying drawings, in which—

Figure 1 shows a side elevation with portions cut away. Fig. 2 shows a plan or top view with part section through xx of Fig. 1. Fig. 3 is a section through yy of Fig. 2 with the hub A revolved ninety degrees. Fig. 4 is a rear elevation with parts cut away. Fig. 5 is a detail of cam G.

A is a hub which fits into a socket in the handle B. Two jaws, C C', slide in grooves in the front part of the hub A. These jaws are connected by the right-and-left handed 30 screw D, so arranged that when the screw is turned in one direction the jaws approach, and when turned the opposite way they recede from each other. The screw D has a beveled gear, d, which meshes into the beveled gear e. 35 The thumb-piece E turns the gear e by means of the shaft e' passing through the hub A. A stop, f, prevents the gear d from slipping away from the gear e.

On that part of the hub which passes through 40 the handle B are two toothed ratchets, aa' , the teeth of each ratchet pointing in the opposite direction from the teeth of the other. Two catches, F and F', play in the ratchets a and a' . Each of these catches F F' allows its ratchet 45 to turn in one direction, and prevents it from turning in the opposite direction, and when they are both held against the hub they prevent it from turning in either direction. The catches F and F' consist of straight bars 50 beveled at their upper ends and fitted in re-

cesses in the handle B. Around each catch is coiled the spring f', which presses the catch upward at all times. The lower ends of the catches are widened out and formed into shoulders or projections f'' . The ring G is slipped 55 over the handle B, and its lower edge rests on the projections f'' , or, rather, these projections are continually pressed against the edge of the ring by the springs f' f''. The lower edge of the ring G contains the stop or projection g 60 and the level portion g' , which drops below the rest of the edge, and each end of which is beveled off in the form of an inclined plane or cam, g' and g'' . The two catches F F' catch under the ring G on opposite sides. The ring 65 or cam G is so arranged that when it is turned in one direction the inclined plane g' catches under the catch F' and forces it down and away from its ratchet, the stop g meanwhile bringing up against the catch F. When the ring 70 G is turned in the opposite direction, the inclined plane g' takes the catch F and lowers it away from its ratchet. (See dotted lines, Fig. 4.) When the ring is placed in a position intermediate between these points, as in 75 Fig. 5, both catches rest against their respective ratchets.

H is a collar to prevent the hub A from slipping from handle B.

Having thus described the manner of constructing my device, I now proceed to show its manner of operation.

When the jaws of the wrench are to be adjusted to any nut, the thumb-piece E is turned in the proper direction and the jaws C C' moved 80 to the proper distance from each other. These jaws may be of various shapes to fit different kinds of nuts. If it is desired to turn the nut with a ratchet motion, the ring G is turned in the proper manner, lowering one of the catches, 85 F or F', away from its ratchet. This being done, the wrench may all be turned in one direction, the handle then drawn back, and a new position secured, as in the well-known ratchet-wrenches now in use. 90

It is evident that by suitably adjusting the ring G, I can secure a ratchet motion in either direction, or I can make an ordinary wrench.

I claim as my invention—

1. A ratchet-wrench composed of the jaws 100

C C', operated by the gears *d e* and thumb-piece *E*, combined with the hub *A*, with its toothed ratchets *a a'*, and the catches *F F'* controlled by the ring *G*, substantially as shown and described.

2. In a ratchet-wrench, the jaws *C C'*, worked by the screw *D* and gears *d e*, and thumb-piece *E*, combined with the double ratchet *a a'* and the catches *F F'*, substantially as shown and described.

3. In a ratchet-wrench, the double ratchet *a a'*, combined with the two catches *F F'*, compressed upward by the springs *f' f'*, and con-

trolled by the cam *G*, substantially as shown and described.

4. In a ratchet-wrench, the double ratchets *a a'*, acted on by two catches, *F F'*, controlled by cam *G*, combined with jaws *C C'*, sliding in hub *A*, substantially as shown and described.

In testimony whereof I affix my signature in presence of two witnesses.

BRADFORD F. LANCASTER.
